No. 851,548.

PATENTED APR. 23, 1907.

J. C. McQUILKIN.

WRENCH.

APPLICATION FILED SEPT. 17, 1906.

UNITED STATES PATENT OFFICE.

JAMES C. McQUILKIN, OF INDUSTRY, PENNSYLVANIA.

WRENCH.

No. 851,548.

Specification of Letters Patent.

Patented April 23, 1907.

Application filed September 17, 1906. Serial No. 334,956.

To all whom it may concern:

Be it known that I, JAMES C. McQUILKIN, residing at Industry, in the county of Beaver and State of Pennsylvania, have invented a new and Improved Wrench, of which the following is a specification.

My invention relates to certain new and useful improvements in wrenches, and in its generic nature it comprises a wrench of the sliding jaw type, having a special construction of handle member and fixed jaw shank and an improved type of double threaded operating screw and collar therefor which cooperates with the handle and the sliding jaw.

Primarily, my invention has for its object to provide a very simple and effective construction of wrench of the foregoing type, which can be easily and cheaply manufactured and which will readily and effectively serve its intended purposes.

In its more detailed nature, my invention comprises certain new and useful improvements over the type of wrench disclosed in the patent to Jas. N. Byington, granted June 6, 1876, No. 178,408.

I have produced a wrench in which the screw lies closed against the shank, the collar has no motion up or down on the screw alongside the shank, but is held in one position relative to the shank by projecting into a cut-away portion of the shank (and held adjacent the handle) and in which handle and fixed shank are so connected as to afford a maximum strength and rigidity of parts, and relieving as much as possible the strain on the connecting parts.

With other objects in view than have been heretofore specified, the invention also comprises certain other novel construction combination and arrangement of parts, all of which will be first described in detail, and then be specifically pointed out in the appended claims, reference being had to the accompanying drawings, in which:

Figure 1, is a perspective view of my invention. Fig. 2, is a central, vertical, longitudinal section thereof. Fig. 3, is a cross section on the line 3—3 of Fig. 2. Fig. 4, is a similar view on the line 4—4 of Fig. 2. Fig. 5, is a perspective view of the fixed jaw and

shank. Fig. 6, is a perspective view of the handle.

Referring now to the accompanying drawings, in which like letters and numerals of reference, indicate like parts in all of the figures, 1 designates the fixed jaw which may be of any approved type, and from which an integrally formed shank 1^a projects downwardly. The shank 1^a is made practically the full length of the tool and is provided with rivet receiving apertures 1^b—1^b suitably spaced apart as indicated. At a suitable distance between the head, the fixed jaw 1 and the bottom of the shank 1^a, the shank 1^a is cut away as at 1^c to form a rectangular shoulder 1^d and a hook like shoulder 1^e, for purposes presently to be explained.

Upon the shank 1, the sliding jaw 2 is mounted and the jaw 2 may be of any approved type or design, but as shown in the drawings, the jaw 2^a which is apertured at 2^b to permit passage of the shank 1^a, and which is connected through a threaded barrel 2^c with a yoke member 2^d that has an aperture 2^e alining with the aperture 2^b and also to permit passage of the shank 1^a.

The yoke 2^d has a threaded portion merging with an internally threaded portion 2^g of the barrel 2^c to receive the screw 3.

The screw 3 in my invention is of similar construction to that shown in Patent No. 178,408, before referred to, and comprises the oppositely threaded portions 3^a and 3^b, the threaded portion 3^a cooperating with the threaded portion 2^g of the barrel 2^c and yoke 2^d of the sliding jaw.

The handle member 4, it will be observed is formed with parallel side members 4^a—4^a having rivet or screw receiving apertures 4^b to cooperate with a similar aperture 1^b in the shank 1. Screws or rivets 5 pass through the apertures 4^b and 1^b and serve to secure the handle 4 on the shank 1^a. The handle 4 also comprises a threaded boss 4^c having an internally threaded portion 4^d to cooperate with the threaded portion 3^b of the screw 3, and the handle 4 has its boss 4^c provided with a shank engaging face 4^e whose lower extremity is provided with a hook-like edge 4^f to cooperate with the edge 4^e of the shank 1^a and lock the shank and handle member

together, it being understood that the surface of the face 4^e projects inwardly from the edge 4^g of the handle, a sufficient amount to enable it to engage the shank face of the cut 5 away portion 1^e .

At its lower portion the members 4^a are joined by a front plate 4^h as shown, the handle member being shown arranged as to leave an open space 4^k at the front, and the 10 side members 4^a are grooved on their outer faces as at 4^m to lighten the construction thereof.

Upon the screw 3 a collar 6 is loosely held, which collar has a central aperture 6^a of sufficient 15 diameter to permit free passage of the screw 3, and the collar 6 is apertured as at 6^b to receive a screw lug 7, as indicated, the lug 7 projecting into the central aperture 6^a , as shown. The screw 3 has a longitudinal 20 groove 3^c , extending about one-half its length, into which groove the screw lug 7 projects and causes the collar and screw 3 to turn together as one. The collar 6 is prevented from riding up and down on the screw 25 3 with respect to the shank 1 by reason of the shoulder 1^d of the shank, the collar 6 projecting into the cut away portion 1^e of the shank. The collar 6 may have its outer face serrated if desired. Thus it will be noticed that by 30 arranging the parts as shown and described, the collar 6 will lie adjacent the handle 4 and always will be held in such position, and hence the operator may with the same hand that holds the tool, by grasping the collar 6 35 with his thumb and first finger adjust the wrench to any desired degree.

By reason of the cut away portion 4^k in the handle 4, when it is desired to detach the handle from the shank 1^a , the screws 5 are 40 removed and by pushing against the shank through the aperture 4^k , the shank can be readily moved to release the engagement of the handle shoulder 4^f with that of the shank 1^e and the shank may be withdrawn, it being 45 understood that the sliding jaw and screw and its connections with the handle and the sliding jaw are sufficient to permit the shank to be moved as shown in dotted lines in Fig. 2, to disengage the shank and handle. It 50 will also be noticed that by bringing the screw 3 close up to the shank 1^a , all danger of bending or injuring the screw and its adjustment is avoided since the shank forms as it were, a guard for the screw.

From the foregoing taken in connection with the accompanying drawings, it is thought the complete construction, operation and numerous advantages of my invention will be readily understood, by those skilled in 55 the art to which it appertains, and I desire to say that many slight changes in the detailed construction, combination and arrangement

of parts may be made without departing from the spirit of the invention or that of the appended claims.

65

What I claim is:—

1. A wrench comprising a fixed jaw shank, a handle member having a groove to receive the fixed jaw shank, shoulders on the fixed jaw shank and on the handle member for interlocking with each other, means for securing the handle member and the shank together, a sliding jaw held on the shank, a double threaded screw connecting the handle member and the sliding jaw, a collar loosely held on said screw to turn therewith, said shank member having means for retaining the collar in position adjacent the handle, substantially as shown and described.

70

2. The combination with a fixed jaw and shank, said shank having a cut away portion to form shoulders, of a sliding jaw held on the shank, a handle member removably secured to the shank and having a portion projected into the cut away portion of the shank and 75 interlocked therewith, and a double threaded screw connecting the handle member and the sliding jaw, a collar loosely held on the screw, means connecting the screw and collar to rotate together, and means for holding the collar always adjacent the handle, substantially as shown and described.

80

3. A wrench comprising in combination a fixed jaw and shank, a sliding jaw mounted on the shank, a handle member removably 95 mounted on the shank and having a screw receiving portion, a screw connecting the handle member and the sliding jaw, means for manipulating said screw to move the sliding jaw, said handle member comprising a 100 pair of side plates straddling the fixed shank, securing means passing through the side plates and the fixed shank, and means carried by the handle member and by the fixed shank for interlocking the same, substantially 105 as shown and described.

105

4. A wrench comprising in combination a fixed jaw and shank, a sliding jaw mounted on the shank, a handle member removably mounted on the shank and having a screw 110 receiving portion, a screw connecting the handle member and the sliding jaw, means for manipulating said screw to move the sliding jaw, said handle member comprising a pair of side plates straddling the fixed shank, 115 securing means passing through the side plates and the fixed shank, means carried by the handle member and by the fixed shank for interlocking the same, said last named means comprising a hook-like shoulder on the shank, and a similar shoulder on the handle to interlock with the shank shoulder, substantially as shown and described.

120

5. A wrench of the class described, com-

prising a fixed jaw and shank, said shank having a cut away portion provided with a rectangular shoulder at one end and a hook-like shoulder at the other end, a handle member secured to said shank and having a portion for entering the cut away portion of the shank, and provided with a hook-like shoulder to cooperate with the similar shoulder of the shank, and said handle member including

5 side plates for straddling the fixed shank and a front connecting plate, and having a screw receiving portion, substantially as shown and described.

J. C. McQUILKIN.
